CLAIM

The ornamental design for an earring, as shown and described.

DESCRIPTION

FIG. 1 is a right side elevational view of an earring showing my new design;

FIG. 2 is a front elevational view thereof;

FIG. 3 is a front elevational view of an earring showing a modified form of my new design; and

FIG. 4 is a left side elevational view of the first form. The rear of both embodiments is plain and unornamented and the second embodiment is a mirror image of the first embodiment.
